CHEST

Filed Aug. 24 1921

INVENTOR.
Laurence E. Collins,
BY *J. A. Bishop.* ATTORNEY

UNITED STATES PATENT OFFICE.

LAURENCE E. COLLINS, OF CANTON, OHIO.

CHEST.

Application filed August 24, 1921. Serial No. 494,911.

To all whom it may concern:

Be it known that I, LAURENCE E. COLLINS, a citizen of the United States, residing at Canton, in the county of Stark and State 5 of Ohio, have invented a new and useful Chest, of which the following is a specification.

This invention relates to chests and more particularly to chests or trunks for the storage 10 of clothing and the like.

The principal object of the invention is the construction of a device of this class that will be absolutely dust proof when closed.

Another object is the construction of the said chest, with fire and heat resisting qualities thereby affording protection to the contents thereof.

A further object is the construction of 20 a chest without the use of nails, screws, rivets or other similar fastening devices, the several parts being held in position by the use of moulding strips on which are formed rounded beads which snap into grooves.

A still further object is the combining of 25 the above features with a lining having insect repelling properties.

In the drawings, in which similar numerals of reference indicate corresponding 30 parts;

Fig. 1 is a cross sectional view of my improved chest.

Fig. 2 is a fragmentary detail perspective of a portion of the outer section of the 35 cover of my chest.

Fig. 3 is a similar view of a portion of the moulding secured to the cover or lid, showing the interlocking bead and tapered groove.

Fig. 4 is a similar view of a portion of 40 the outer section of the body of the said chest.

Fig. 5 is a similar view of a portion of the moulding secured to the body, showing the interlocking bead and tapered tongue.

Fig. 6 is an enlarged elevation of one of the handles, and

Fig. 7 is a modified form illustrating my 50 invention employed in a chest constructed entirely of metal.

In the embodiment of my invention, I form of heavy gauge sheet metal, preferably steel, an outer shell 1 which is rectangular in shape and of convenient proportions for the purpose. A bottom 2, also

of sheet metal, is secured by spot welding or other suitable process, to inturned flanges formed on the lower extremities of the walls of the shell. Extending longitudinally of the shell, and spot welded to the sheet 2 at spaced intervals, is a plurality of channel members 4 which are preferably formed of rolled sheet metal, and spaced slightly from the bottom sheet and 65 spot welded to the side sheets, are similar channel members 5.

Adjacent the upper edge of each of the side sheets is a down turned flange 6, which may either be a portion of the side sheet 70 or spot welded thereto. The lower extremity of the flange 6 is curved outwardly, upwardly and inwardly toward the sheet, thus forming a groove 7 as shown in Fig. 4. Fitting within the groove 7 is a rounded 75 bead 8 which is formed on one edge of a sheet metal moulding, indicated generally at 9. Extending upwardly from the bead 8 is a vertical portion 10 which is designed to lie against the inner wall of the flange 6 80 when the bead 8 is positioned in the groove 7, the inwardly turned free edge of the metal forming the groove being designed to exert a constant pressure against the said bead, causing the portion 9 to bear firmly 85 against the said inner wall of the flange. A horizontal portion 11 extends from the vertical portion 9 toward the interior of the chest and from the said horizontal portion rises a tapered tongue 12. The moulding 90 descends vertically from the base of the tongue opposite the portion 11 and is provided with the inverted channel 14, as clearly shown in Fig. 5.

A sheet of asbestos 15 which is made to 95 exactly fit within the shell 1, is placed upon the channel members 4, the periphery of the said sheet being positioned under the channel members 5. A sheet 16 of asbestos is then placed vertically at each side of the 100 chest, its lower end fitting against the channel 5 while its upper end rests against the wall of the channel 14. A lining formed of wood is placed inside of the asbestos, the said lining consisting of the bottom 105 section 17 and the side walls 18. It will be seen that the edges of the bottom section are beveled to fit similar beveled edges on the lower edges of the side walls. By this construction, I am enabled to place the 110 bottom section 17 in position and spring the side wall sections 18 in between the said

bottom section and the channels 14. It will thus be seen that a very solid construction is effected without the use of nails, screws or other similar devices. The wood of which the lining is formed will preferably be cedar, camphor wood or the like with an insect repelling fragrance altho it will be understood that any kind of wood may be used and if it is desired to employ the chest for the storage of clothing or other articles subject to the ravages of moths, the wood may be impregnated with an insect repellent.

The lid of my chest is substantially similar in construction to the body portion, the top and side portions thereof being formed of sheet metal. At the lower edge of each of the side portions 19 of the lid is formed a groove 20, similar to the grooves 7 and 24 into each of the grooves 20 fits a bead 21 similar to the beads 8. The bead 21 is formed on one edge of a metal moulding generally indicated at 22, the said moulding being provided with a tapered groove 24 which is designed to receive the tapered tongue 12. The edge of the moulding opposite the bead 21 is bent to form a shoulder 25 which is designed to receive a wood lining 26. A sheet of asbestos 27 lies against channels 28 which are spot welded to the top of the lid and forms a backing for the lining 26.

The hinges, one of which is shown at 23, will be positioned so that the bending point 35 is slightly below the joint formed by the meeting of the lid and the body portion. This produces a slightly eccentric relative movement between the lid and body when the said lid is closed. Handles 29 are rotatably hung in lugs 30 secured to the lid and a cross bar on each handle is designed to engage the under side of a lug 32 and draw the lid down tightly when the said handles are forced inwardly. By this arrangement of the hinges and handle, when the lid is closed and the handles are pressed inwardly, it causes a wedging action between the tapered tongues 19 and the tapered grooves 24, forcing the one firmly within the other and producing an absolutely dust and moisture tight joint.

In Fig. 7 I have illustrated a slightly modified form of my invention. The moulding strip 40 on which is formed the tapered tongue 41, is made integral with the side wall and is provided on its inner edge with a rounded groove 42 similar to the

grooves 7 and 20 in the preferred form of the invention. A rounded bead 44, similar to the beads 8 and 21, is formed on the upper edge of a sheet 45 which forms the side wall lining of the chest. A rounded groove 46 is formed on the lower edge of the sheet 45 and receives a bead 47 formed on the edge of the bottom lining sheet 48.

The moulding strip 49, corresponding to the moulding 25 of the preferred form, is made integral with the side walls of the lid and has formed therein the tapered groove 50 to fit over the tongue 41. A rounded groove 51 on the inner edge of the moulding 49, receives the bead 52 formed on the edge of the top lining sheet 54. In this form, the chest is made entirely of sheet metal, and as in the preferred form, no nails, rivets, screws or other fastening devices of a similar nature, are used, the several parts being assembled by snapping the beads into the rounded grooves.

It is obvious from the foregoing that when my chest is closed and the handles pressed into place, it is absolutely proof against dust, moisture or the attacks of vermin. It will be seen that by the construction employed, the assembling may be done very rapidly, thereby reducing the amount of labor and consequently enabling me to manufacture the article at a low cost.

It will also be seen that by spacing the inner wall of asbestos away from the outer metal wall, a dead air space is formed which will provide additional protection from fire, to the contents of the chest.

Having now described my invention, what I claim is:

1. A chest comprising an outer shell and a lining spaced therefrom and within said shell, a spring groove carried by said shell, a moulding strip, a bead formed on said moulding strip and designed to fit within said spring groove, the said moulding securing the said lining in spaced relation to said shell.

2. A chest comprising an outer shell and a lining spaced therefrom, a spring groove carried by said shell, a moulding strip, a bead formed on said moulding strip and designed to fit within said spring groove, and a channel portion upon said moulding strip or engagement with the lining or securing the same in spaced relation to the shell.

In testimony that I claim the above, I have hereunto subscribed my name.

LAURENCE E. COLLINS.
